UNITED STATES PATENT OFFICE

1,947,832

FASTENING DEVICE FOR SECURING THE
HEAD OF A HAMMER, HATCHET, OR THE
LIKE

George E. Dobbins, Philadelphia, Pa.

Application June 18, 1932. Serial No. 617,935

3 Claims. (Cl. 306—33)

My invention relates to a new and useful fastening device for securing the head of a hammer, hatchet, or the like, to its supporting handle in a detachable manner and yet in a manner calculated completely to prevent the accidental flying off or detachment of the head of the hammer or hatchet from its conventional wooden handle thereby entirely eliminating all danger of injury resulting from the accidental disengagement of 10 the head of the hammer or hatchet during use.

To the above ends, my invention consists of a cleat having an elongated body portion adapted to be wedged between the hammer head and the wooden handle engaging said head and the seat 15 within a groove in the body of said handle, means for securing said body portion to said hammer, oppositely disposed lugs adapted to overlap and engage the outer edges of said head, and a wedge shaped lug at right angles to said oppositely disposed lugs and said body portion and adapted to be wedged into the edge of the wooden handle to expand the latter and insure rigid engagement of the wooden handle with the head mounted thereon.

25 My invention further relates to various other novel features of construction and advantage, all as hereinafter described and claimed in connection with the accompanying drawing, in which:

Figure 1 represents a side elevation of the upper 30 portion of a hammer handle to which the head of a hammer has been secured by the fastening device embodying my invention.

Figure 2 is a top plan view of Figure 1.

Figure 3 is a section on line 3—3 of Figure 1.

35 Figure 4 is a section on line 4—4 of Figure 1.

Figure 5 is a section on line 5—5 of Figure 2.

Figure 6 represents a perspective view of the 40 novel fastening device of my invention shown detached.

Referring to the drawing in which like reference characters indicate like parts, 1 designates a handle on which the head 2 of a hammer, hatchet or any other instrument is mounted by insertion of the upper end 3 of the handle 1 through the opening 4 usually provided in the head 2. The upper portion 3 of the handle 1 is preferably provided with continuous shoulder 5 which is adapted to engage the bottom edge of the skirt 6 forming part of the hammer head 2, as will be seen from Figure 5. In order to fasten the head 2 of the hammer to the handle 1 in a manner which will prevent the accidental detachment and yet permit of easy detachment, I have devised a novel fastening device 8 which 55 consists of the body portion 9 having the tap hole

10 and which terminates at its upper end in the oppositely disposed lugs 11 and 12 at right angles to the body portion 9 and with the pendant wedge 13 extending from one of the lugs 11 and 12 and disposed at right angles to said lugs and 60 the said body portion 9, as will be best seen in Figure 6. The upper portion 3 of the handle 1 is provided with the groove 14 which is adapted to receive the body portion 9 of the cleat 8 and is further provided with the hole 15 aligning with 65 the hole 10 to receive the screw 16 passing through the handle 1 and engaging the tap hole 10, the head of the screw 16 being countersunk in the other side of the handle, as will be best seen from Figures 3 and 4.

The operation of my fastening device is as follows: The head 2, which, as stated, may be that of a hammer, hatchet, or any other instrument, is slipped over the upper portion 3 of the handle 1 until the bottom edge of the skirt 6 rests upon 70 the shoulder 5. In this position the upper edge of the handle is flush with the upper edge of the head, as seen in Figure 5. The cleat 8 is then inserted, so as to cause the body portion 9 thereof to seat within the groove 14 in the body of the 75 handle and is forced down until the bottom edge 18 of the cleat 9 rests upon the shoulder 19 in the bottom of the groove 14. In this position the hole 15 aligns with the hole 10 and the screw 16 is driven from the opposite side of the handle 1 80 to engage the tap hole 10, as seen in Figure 3. While forcing the body portion 9 of the cleat 8 into the groove 14 in the manner aforesaid, the wedge 13 is simultaneously driven into the upper portion 3 of the handle 1, thus expanding the 85 latter within the opening 4 in the head 2 and causing frictional engagement. When the cleat 9 has been forced downwardly into position so that the hole 10 thereof aligns with the hole 15, the handle 1 and oppositely disposed lugs 11 and 12 which overlap the corresponding edges of the 90 head 2 are in firm contact with the head, as will be best seen in Figures 2 and 3. Thus the lugs 11 and 12 firmly engaging the head 2 and being integral with the body portion 9 which is anchored to the handle 1 by the screw 16, together with the frictional engagement of the head 2 with the upper portion 3 of the handle, due to 95 expansion of the latter by means of the wedge 13, completely insure against accidental detachment 100 of the head 2 from the handle 1. If, on the other hand, it is desired to remove the head 2 from the handle 1, it is merely necessary to disengage the screw 16 and then to pull the wedge 13 out from 105 engagement with the upper portion 3 of the han- 110

dle, whereupon the head 2 can be easily removed. Having thus described my invention, what I claim as new and desire to secure by Letters Patent is:

- 5 1. A fastening device for securing the head of a hammer or similar tool to the handle or stock thereof, comprising an elongated body portion adapted to engage a seat in the outer, head-supporting end of said handle, and having its bottom 10 inner edge rounded to prevent cutting of said handle during application of said fastening device, oppositely disposed lugs at the outer end of said body portion, adapted to straddle the outer face of the head of such tool and the outer end 15 of said handle, a wedge carried by one of said lugs substantially parallel to said body portion and adapted to be driven into the outer end of said handle, and means for preventing movement of said fastening device with respect to said handle 20 comprising a shoulder in said handle against which the inner end of said body portion is adapted to abut and an engaging device passing through said body portion and said handle.
2. A fastening device for securing the head of a hammer or similar tool to the handle or stock 25 thereof, comprising an elongated body portion adapted to engage a seat in the outer, head-supporting end of said handle, oppositely disposed

lugs at the outer end of said body portion, adapted to straddle the outer face of the head of such tool and the outer end of said handle, a wedge carried by one of said lugs substantially parallel to said body portion and adapted to be driven into the outer end of said handle, and means for preventing movement of said fastening device with respect to said handle comprising a shoulder in said handle against which the inner end of said body portion is adapted to abut and an engaging device passing through said body portion and said handle.

80

3. A fastening device for securing the head of a hammer or similar tool to the handle or stock thereof, comprising an elongated body portion adapted to engage a seat in the outer, head-supporting end of said handle, oppositely disposed lugs at the outer end of said body portion, adapted to straddle the outer face of the head of such tool and the outer end of said handle, a wedge carried by one of said lugs substantially parallel to and spaced from said body portion and adapted to be driven into the outer end of said handle, and means for preventing movement of said fastening device with respect to said handle comprising an engaging device passing through said body portion and said handle.
